UNITED STATES PATENT OFFICE

CLARENCE T. ROADES, OF LOUISE, TEXAS

MAIL HOLDER AND STACKER

Application filed May 29, 1930. Serial No. 457,487.

This invention relates to a device particularly adapted for use in the holding and stacking of mail.

It is aimed to provide a novel construction in which the mail may be readily applied and readily removed and in which the parts are adjustable according to the size of matter to be held or stacked.

It is aimed to provide an exceedingly simple, efficient and durable construction which may be manufactured at minimum cost.

The more specific objects and advantages will become apparent from a consideration of the description following taken in connection with accompanying drawings illustrating an operative embodiment.

In said drawings:

Figure 1 is a view of the device in side elevation,

Figure 2 is an end view looking from the left in Figure 1,

Figure 3 is a cross sectional view taken on the line 3—3 of Figure 1,

Figure 4 is a cross sectional view taken on the line 4—4 of Figure 1, and

Figure 5 is a cross sectional view taken on the line 5—5 of Figure 1.

Referring specifically to the drawings, 10 designates a base or supporting plate adapted to be disposed on a table, counter or supported in any desired manner. Disposed over the base and of a size substantially the same as the base, is a supporting plate 11 which is vertically movable relatively to the base. Guide rods 12 are rigidly connected to the base 10 adjacent one end thereof by nuts 13 engaging opposite sides of the base and which guide rods extend loosely through openings 14 in the plate 11 and above the same have nuts 15 or an equivalent stop thereon.

A pair of vertically disposed hold-down rods or members 16 for mail matter are movable to adjusted positions longitudinally of the plates 10 and 11 being accommodated in elongated slots 17 and 18 of such plates. Such rods 16 also extend through an adjusting plate 19 which is movable longitudinally on the base 10 so as to adjust the rods and the same is equipped with a bolt 20 movable in

an elongated slot 21 at such base and adapted for tightening to secure the plate 19 and members 16 rigidly in different adjusted positions. In addition, the rods 16 are held against downward displacement through the engagement of nuts 22 thereon with the opposite sides of said base 10.

To coact with the hold-down members or rods 16 another pair of hold-down rods or members are provided as at 23, the same being connected together by a handle as at 24. The rods 23 engage in notches or cut-away portions 25 in the adjacent end of the plate 11 and hence the rods 16 and 23 as well as the rods 12 serve as vertical guides for the plate 11. The mail matter or the like is disposed on the plate 11 between the rods 23 and 16 and is adapted to be held down by loops or grips 26 thereon, the plate 11 being depressed as the piles of mail matter increase beneath the grips 26. Expansive coil springs of any suitable type or the equivalent, may be provided at 27 between and in engagement with the plates 10 and 11 to force the plate 11 upwardly.

The grips 26 are pivotally mounted as shown at 23^a on rods 16 and 23, and are normally held in extended positions by means of contractile coil springs 26^a connecting an extension 26^b of each grip 26 with the rod 16 or 23 on which the grip is mounted. In order that rods 23 may be swung aside to permit removal of a bundle of mail after it has been tied up, said rods are carried by a bar 28 which has hinge leaves 29 arranged adjacent hinge leaves 30 connected to the plate 10. A pintle or rod 31 removably passes through the leaves 29 and 30 and a coil spring 32 surrounds the rod 31 and is engaged with the parts as shown so as to form a spring hinge and normally maintain the rods 23 in the position shown in the drawings.

It will thus been seen that the rods 16 may be moved to any desired position to adjust the parts according to the size of mail matter to be held and stacked and that the mail matter is forced downwardly between and beneath grips 26 onto the platform 11. The arrangement is such that the stacked mail matter may be readily strapped and when the

stack is to be removed, the handle 24 may be moved outwardly to the dotted line position shown in Figure 1, thus completely releasing the entire stack so that it may be 5 readily removed.

Various changes may be resorted to provided they fall within the spirit and scope of the invention.

I claim as my invention:—

10 1. A device of the class described comprising a base, a plate above said base to receive stacked material, hold-down means for the stacked material, said hold-down means constituting a guide for vertical movement of the plate, and including grip means pivotally secured thereto and means urging upward movement of the plate.

20 2. A device of the class described comprising a base, a plate above the same to receive stacked material, hold-down means for the stacked material secured to said base, said hold-down means constituting a guide for vertical movement of the plate, said hold-down means including grip means pivotally secured thereto and arranged above the plate to cooperate therewith in holding the stacked material, and spring means urging the plate toward said grip means.

30 3. A device of the class described comprising a base, a plate above said base to receive stacked material, hold-down means for the stacked material, said hold-down means constituting a guide for vertical movement of the plate, means urging upward movement of the plate, and means whereby said hold-down means is adjustable according to the size of matter to be stacked.

40 4. A device of the class described comprising a base, a first hold-down means, a second hold-down means, said first and second hold-down means being secured to said base, a plate to receive stacked matter guided in its movement by said hold-down means, means urging upward movement of the plate, the material to be stacked being adapted for engagement with each of said hold-down means, and means mounting the second mentioned hold-down means for movement away from the first mentioned hold-down means 50 to release the stack.

55 5. A device of the class described having a base, a plate to receive stacked material, a hold-down means for said material extending above the plate, a second hold-down means for said material extending above the plate, the first and second hold-down means being secured to said base and constituting a guide for the plate, means urging upward movement of the plate, and means mounting the second hold-down means for movement away from the first hold-down means to release a stack.

60 6. A device of the class described comprising a base, a hold-down means rising from the base, second hold-down means, the lat-

ter hold-down means being pivoted to the base, a plate vertically movable on said hold-down means, means urging upward movement of the plate, and said plate being notched to accommodate the movement of the 70 second hold-down means.

7. A device of the class described comprising a base, a plate slideable along the base, a hold-down means rising from the base, a plate over said base vertically movable on said hold-down means, spring means between the base and second mentioned plate urging upward movement of the second mentioned plate, said second mentioned plate having elongated slots through which the hold-down means pass in order to permit adjustment thereof, said second mentioned plate having notches in one end thereof, hold-down members engaging said notches, a handle connecting said members, and spring hinge 85 means securing said members to the base and normally urging the same into said notches.

In testimony whereof I affix my signature.

CLARENCE T. ROADES.
